Des. 239,591

Patented Apr. 20, 1976

239,591

SUCTION NOZZLE OR THE LIKE

Robert M. Goodman, 9024 Moody Ave.,
Morton Grove, Ill. 60053

Filed Mar. 14, 1975, Ser. No. 558,318

Term of patent 14 years

Int. Cl. D7—05
U.S. Cl. D7—173

Fig. 1

Fig. 2

F₁ 3

F₁ 4

FIG. 1

FIG. 2

FIG. 1 is a perspective view from the rear of a suction nozzle or the like embodying my design;

FIG. 2 is a top plan view thereof;

FIG. 3 is a front elevational view thereof;

FIG. 4 is an elevational view of the right side thereof;

FIG. 5 is a rear elevational view thereof; and

FIG. 6 is a bottom plan view of the suction nozzle or the like.

The electrical cord has been shown fragmentarily in FIGS. 1, 2 and 5 for ease of illustration and to indicate indeterminate length.

I claim:

The ornamental design for a suction nozzle or the like, as shown and described.
